UNITED STATES PATENT OFFICE.

EUGENE S. FOLJAMBE, OF DREXEL HILL, PENNSYLVANIA.

WHEELED-TOY WATER-CRAFT.

1,296,277.

Specification of Letters Patent. Patented Mar. 4, 1919.

Application filed April 18, 1918. Serial No. 229,386.

To all whom it may concern:

Be it known that I, EUGENE S. FOLJAMBE, a citizen of the United States, residing at Drexel Hill, in the county of Delaware and 5 State of Pennsylvania, have invented a certain new and useful Wheeled-Toy Water-Craft, of which the following is a specification.

The principal object of the present invention is to provide wheeled toy water-craft for use by comparatively young children, the toy being so designed that a fore and aft rocking motion may be experienced by the occupant during forward and astern 10 movements of the conveyance as propelled through the medium of a push-pole. A further object of the present invention is to provide a toy of the character stated so designed that the same may be readily 15 sized at the will of the occupant. A still further object of the present invention is to provide wheeled toy water-craft of light, durable and comparatively inexpensive construction which may, if desired, be used in 20 doors without deleterious effect to wood-work, wall paper, furniture and the like should the toy come in contact therewith. Other and further objects of the present invention reside in the provision of wheeled 25 toy water-craft characterized by certain new and novel arrangements, connections, constructions and combinations of parts more 30 fully pointed out hereinafter.

The invention consists of the improvements hereinafter described and finally claimed.

The nature, characteristic features and scope of the invention will be more fully understood from the following description 40 taken in connection with the accompanying drawings forming part hereof, and in which:

Figure 1 is a view in side elevation, partly sectioned, of a toy canoe embodying features of the invention.

Fig. 2 is a top or plan view thereof.

Fig. 3 represents a blank hereinafter referred to, and

Fig. 4 is a view in elevation of the push-pole.

For the purpose of illustrating my invention, I have shown in the accompanying drawings one form thereof, which is at present preferred by me, since the same has 55 been found in practice to give satisfactory and reliable results, although it is to be un-

derstood that the various instrumentalities of which my invention consists can be variously arranged and organized and that my invention is not limited to the precise arrangement and organization of the instrumentalities as herein shown and described.

Referring now to the drawings in detail, there is shown for illustrative purposes, a toy symbolic of a canoe although obviously other forms of water-craft may be symbolized with equally good results. However, because a canoe construction may be lightly and inexpensively designed it is particularly adaptable for toy purposes, particularly in-doors. In practice, the parts are made principally of wood and a heavy grade of paper. In the drawings 10 designates the hull of the canoe. In practice, good results have been obtained by employing a heavy grade paper for the purpose. Best results have been obtained by shaping a blank 10' as shown in Fig. 3 and forming same around the keel and bow and stern posts which may be of wood and securing the same thereto as by tacks or equivalent means. The keel comprises the flat strip 11 having secured thereto, fore and aft, a bow post 12 and a stern post 13 which latter, in cross-section, are relatively wedge-shaped 15 and exteriorly are each grooved to accommodate a buffer 14, for instance rope, which may be glued or otherwise secured to place. Fixed to the underside of the strip 11 are athwart pieces 15, 16 and 17, for instance, one amid-ship and at the bow and one at the stern. Secured to these pieces are longitudinal strips 18 paralleling the strip 11. Such structure serves to provide a substantial bottom for the canoe and provides 20 means for supporting the wheels or rollers to be presently described. Braces 19 may be employed fore and aft to provide rigidity and shoulder rests 21 may also be utilized. If desired, an opening 22 may be 25 provided the ends of the canoe for the accommodation of a tow-line. A bead 23 of suitable material is provided the gun-wale of the canoe to add strength and rigidity. In practice, the above parts are properly 30 finished to give a nautical appearance. Secured to the underside of the athwart piece 15 are spaced wheels or rollers 24 which may be covered with rubber if desired, so as to be relatively noiseless in operation. These 35 wheels or rollers provide means whereby the canoe may be moved from place to place

and are so spaced that the distance between wheel centers is considerably less than is the beam of the canoe, so that the occupant of the canoe can readily cause capsizing thereof if desired. Fore and aft the canoe is provided with other wheels or rollers, preferably casters 25—26 for guiding purposes, the diameter of a caster-roller being considerably less in diameter than that of the 10 wheels 24. This is so that the canoe may be readily tilted fore and aft to provide a pitching movement. The casters are secured to the athwart pieces 16—17 and the rollers may be covered with rubber if desired. 15 The canoe is propelled by employing the push-pole 27 which is shaped in the configuration of a paddle. It may be provided with a rubber tip or ferrule 28 so that a good purchase may be had with respect to 20 the floor or ground. The rubber ferrule also prevents marring of hard wood floors when used in-doors. Obviously, the toy may be used out of doors and if properly waterproofed may be used in small bodies of 25 water.

It will now be apparent that I have devised a novel and useful construction which embodies the features of advantage enumerated as desirable in the statement of the

invention and the above description and 30 while I have in the present instance shown and described the preferred embodiment thereof which has been found in practice to give satisfactory and reliable results, it is to be understood that the same is susceptible of 35 modification in various particulars without departing from the spirit or scope of the invention or sacrificing any of its advantages.

What I claim is:

1. A toy of the character stated comprising a conveyance symbolic of water-craft provided amid-ship with spaced wheels or rollers upon which the conveyance may be propelled and provided fore and aft with 45 guide wheels or rollers arranged to permit of a rocking movement of said conveyance and an adjunct for said conveyance in the form of a push-pole.

2. A toy of the character stated comprising a wheeled conveyance symbolic of water-craft provided with means for permitting of a rocking movement of said conveyance and an adjunct for said conveyance in the 50 form of a push-pole.

In witness whereof, I have hereunto signed my name.

EUGENE S. FOLJAMBE.
